UNITED STATES PATENT OFFICE.

CHARLES NELSON, OF BROOKLYN, AND WALTER G. BARKER, OF NEW YORK, N. Y., ASSIGNORS
TO S. STERNAU & COMPANY, OF NEW YORK, N. Y., A COPARTNERSHIP.

DESIGN FOR A TOWEL-PIN.

No. 39,408.

Specification for Design.

Patented July 7, 1908.

Application filed April 3, 1908. Serial No. 425,063. Term of patent 7 years.

To all whom it may concern:

Be it known that we, CHARLES NELSON, a subject of the King of Sweden, and a resident of the borough of Brooklyn, county of Kings and State of New York, and WALTER G. BARKER, a citizen of the United States, and a resident of the borough of Manhattan, city, county, and State of New York, have invented a new, original, and ornamental Design for a Towel-Pin, of which the following is a specification, reference being had to the accompanying drawing, forming part hereof.

Figure 1 is a plan view of a towel pin showing our new design and Fig. 2 is a side view of the same.

We claim:

The ornamental design for a towel pin, as shown.

CHARLES NELSON.
WALTER G. BARKER.
